UNITED STATES PATENT OFFICE.

WILLIAM C. TYLER AND EDWARD NALL, OF AKRON, OHIO, ASSIGNEES TO THE GOOD-
YEAR TIRE AND RUBBER COMPANY, OF AKRON, OHIO, A CORPORATION OF OHIO.

MACHINE FOR COVERING BEAD-CORES.

1,113,513.

Specification of Letters Patent. Patented Oct. 13, 1914.

Application filed September 22, 1913. Serial No. 791,105.

To all whom it may concern:

Be it known that we, WILLIAM C. TYLER and EDWARD NALL, citizens of the United States, residing at Akron, in the county of Summit and State of Ohio, have invented new and useful Improvements in Machines for Covering Bead-Cores, of which the following is a specification.

This invention relates to improvements in machines for covering the cores, around which are built the beads of pneumatic tire shoes, with a layer of fabric and the object of the invention is to provide an improved machine by which a covering of these cores is quickly, rapidly and economically accomplished.

With the foregoing and other objects in view, the invention consists in the novel construction, combination and arrangement of parts constituting the invention to be hereinafter specifically described and illustrated in the accompanying drawings which form a part hereof wherein is shown the preferred embodiment of the invention, but it is to be understood that changes, variations and modifications can be resorted to which come within the scope of the matter herein-after claimed.

In the drawings in which similar reference numerals indicate like parts in the different figures; Figure 1, is a view in side elevation of a portion of a machine embodying this invention; Fig. 2, is a similar view of the remainder of the machine; Fig. 3, is a plan of that portion of the machine shown in Fig. 1; Fig. 4, is a plan view of the portion shown in Fig. 2; Figs. 5-11 inclusive are end elevations of various rolls and other improvements employed in the device; Fig. 12, is a view partly in section of the device for submerging the core of the bead in a cement bath; Fig. 13, is a transverse sectional view of the bead core approximately on line A of Fig. 3 with a strip of fabric therebelow; Fig. 14, is a view similar to Fig. 13 taken on line B of Fig. 4; Fig. 15, is a view similar to Figs. 13 and 14 taken on line C of Fig. 4; Fig. 16, is an end elevation of one of the folders; and, Fig. 17, is a similar view of the other folder.

Briefly, the beads of pneumatic tire shoes especially of the clincher type are formed continuously by a tube-machine of a composition which when vulcanized will become intensely hard. In order to cause the core

to become perfectly united with the side edges of an open-bellied tire-shoe they are covered with a layer of fabric which ultimately becomes intimately united with the core of the bead and when covered with other layers of fabric forms what is known as the bead of the tire-shoe. Heretofore, the covering of these cores with fabric has been a slow and laborious operation by hand and the results have been neither satisfactory nor have they been economical.

The invention, of which a specific description follows, embodies a supporting instrumentality on which are mounted a series of mechanisms each of which is adapted to perform its respective function in the covering of the bead core with fabric and each contributes to the ultimate production of the covered core.

Referring more specifically to the drawings the entire mechanism is supported upon a table 1 which in turn is supported by pairs of legs 2, 3, 4 and 5. The mechanisms by which the operation of coating the bead core with a strip of fabric, are primarily supported on the upper face of the table 1 and a bead core during its progress will travel from the right to the left in Figs. 1-4.

Secured to the legs 5 are supporting brackets 6 the outer ends of which are provided with bearings for an axle 7 of a reel 8 on which is wound the uncovered and uncured bead core 9. The bead core is carried upwardly from the reel 8 over a guiding roll 10 supported on a suitable bracket 11 on the table 1. Adjacent to the guiding roll 10 and secured to the table 1 is an upright guiding plate 12 provided with a suitable aperture through which the bead core passes to a pair of rolls 13 and 14, (see Fig. 11). The roller 14 is mounted on a shaft 16 and the roller 13 on a shaft 17 both mounted in bearings in a housing 15. The shafts 16 and 17 bear intermeshing spur gears 18 and 19 for causing their revolution in unison. The shaft 16 also bears a sprocket wheel 20 for a purpose to be later described and the outer end of the shaft 16 is supported in an upright bracket 21. The peripheries of the rolls 13 and 14 are formed to constitute rotary trimming shears and the outer lateral edges of the roller 13 are provided with enlarged sharpened flanges which are adapted to engage the edges of the roller 14 and trim off all fins and surplus material.

existing along the side edges of the bead core while the central portions of the two rolls are shaped to receive the bead core.

The trimming rollers 13 and 14 are caused to revolve by the following mechanism: Secured to the under face of the table 1 are brackets 22 which form bearings for and support the horizontal shaft 23 of an armature of an electric motor 24. The armature shaft 23 also bears a pulley 25 (see Fig. 4) adapted to drive a belt 26. Mounted in suitable hangers 27 (see Fig. 2) is a shaft 28 on which is mounted a pulley 29. Also mounted on the under face of the table 1 is a pair of hangers 30 furnishing a support for a rotatable shaft 31 on which is mounted a pulley 32 around which the belt 26 passes. The pulleys 25 and 32 being relatively smaller than the pulley 29 which is between them, the latter also engages the belt 26 during its travel and is thereby revolved. The shaft 28 which bears the pulley 29 also bears a sprocket wheel 33 around which passes a sprocket chain 34 the upper end of which passes around a sprocket wheel 35 on a shaft 36 mounted in a housing 37 on the upper face of the table 1, (see Fig. 4). The shafts 28 and 36 are of sufficient length to permit the sprocket wheels 33 and 35 to be placed at one side of the table so that the sprocket chain from one to the other is permitted. Also mounted on the shaft 36 is a sprocket wheel 38 over which runs a sprocket chain 39 which also runs over a sprocket wheel 40 mounted on the shaft 41 supported at one end by a housing 42 and otherwise supported in a pair of housings 43. The shaft 41 bears a sprocket wheel 44 and extending between the sprocket wheel 20 on the shaft 16 and the sprocket wheel 44 on the shaft 41 is a sprocket chain 45 so that as motion is communicated by the motor 24 through the shaft 36 to the pulley 29 motion is also communicated through the sprocket chain 34 to the mechanism just described.

Mounted at the left, in Fig. 1, of the trimming rolls 13 and 14 is a stationary guiding plate 46 provided with an aperture through which the now trimmed bead-core 47 passes, and to the left of the guiding plate 46 are a pair of housings 48 (see Fig. 5), provided with bearings for a pair of shafts on which are mounted roughing rolls 48 and 49. The upper roll 48 being mounted on a shaft 50 and the lower roll 49 being mounted on a shaft 51. The faces of the rolls 48 and 49 are fashioned to generally approximate the shape of the bead-core and are provided with roughing members or knives 52. These two rolls are adapted to be rotated in a reverse direction to the trimming rolls 13 and 14 and in a direction reverse to the travel of the bead-core 9. The function of these two rolls is to slightly roughen the surface of the bead core so that the subsequently applied

cement will adhere thereto more permanently and become slightly incorporated with the superficial portions thereof. These rolls 48 and 49 are rotated as follows: Mounted on the shaft 31 are a pair of pulleys 53 and 54. Mounted on the shafts 50 and 51 are a pair of pulleys 55 and 56 respectively. Adapted to run on the pulleys 53 and 55 is a belt 56' and connecting the pulleys 54 and 56 is a belt 57 which latter is crossed between the two pulleys so as to cause the roll 48 and 49 to rotate in opposite directions and their peripheral portions having the roughing tools 52 to move in an opposite direction to the movement of the bead core 9. It will be obvious, of course, that the revolutions of the pulleys 53 and 54 is obtained through the medium of the belt 26, already described.

Mounted at the left of and adjacent to the mechanism described in the preceding paragraph are a pair of drawing rolls (see Fig. 6) designated by the reference numerals 58 and 59 between which the trimmed and roughened bead passes and by which its movement is secured. These feed rolls 58 and 59 are mounted on suitable shafts 60 and 61 in the housings 43, this housing like all the housings being provided with suitable boxes for the shafts mounted therein.

The feed roll 59 is provided with peripheral flanges and centrally of the periphery thereof is a circumferentially-extending series of minute points or projections 63 which are adapted to engage the bead core and feed it forward and the peripheral contour of the roll 58 approximately corresponds to the two faces of the bead core which is not engaged by points 63. The rotation of the shaft 41 is secured, as has already been described, through the medium of the sprocket chain or linked belt 39. The small projections 63 are of so minute a character that they do not injure the bead core which they engage and their engagement with the bead core is increased through the medium of the pressing roll 58 which forces the core against these points, thereby effectively securing traction of the points 63 with respect to the bead core.

Mounted on the upper face of the table 1, to the left in Fig. 1, of the housings 43 is a coating tank 64 adapted to contain a liquid cement through which the bead core is arranged to pass and receive a coating of a siccative rubber cement. The tank embodies a body member adapted to contain liquid cement forming a bath and is provided at the right end in Fig. 1 with a pair of arms 65 the outer ends of which are provided with bearings for the shaft of a guiding roller 66 over which the bead core 9 passes. The opposite end of the tank is also provided with a pair of arms 67 provided with bearings for supporting the axle of a

guiding roller 68. In order to hold the strip 9 of bead core submerged in a bath during its progressive movement the following mechanism is employed: (see Fig. 12).

Secured to one side of the tank 64 is a lug 69 provided with a vertical aperture constituting a bearing forming a support for a T-shaped member 70 in which extends a horizontal shaft with one end positioned over the open portion of the tank and on which is fixedly mounted an arm 71 bearing a roller 72. The opposite end of the shaft is provided with a fixedly secured arm 73 the lower end of which is provided with an enlargement 74 in which is a horizontally-shiftable pin 75 adapted to be forced into a suitable aperture in the side wall of the tank for holding the two arms in a determinate position and constituting a locking pin for this purpose. The roller 72 is adapted to hold the strip 9 within the bath during its progressive movement through the medium and if it is desired at any time to permit the passage of the strip 9 without a submersion in the bath the locking pin 75 is withdrawn and the arm 73 oscillated thereby raising the roller 72 out of the bath. Immediately adjacent to, and at the left of the bath 64 is an upright bracket 76 which bears at its upper end a guiding roll 77. The function of the guiding roll 77 is to change the line of movement of the strip 9 toward a drying tank by which the siccative coating placed on the strip in the bath 64 is partially dried and thereby thickened. The drying mechanism consists of an elongated steam jacketed cylinder 78 into the interior of the jacket of which steam is admitted by an inlet pipe 79 and exhausted through a pipe 80. The strip 9 is adapted to pass through the open central portion of the drier and the drying operation is increased by the forcing of compressed air into the cavity in the cylinder 78 through which the strip 9 passes by means of an inlet pipe 81.

To the left, in Fig. 2, of the drying device 78 is an upright bracket 82 which is adapted to revolvably support a guiding roller 83 for guiding the strip 9. The centers of the guiding rollers 77 and 83 are approximately in a horizontal plane so that the strip 9 is easily guided through the drying device just described during its progressive movement.

Secured to the under face of the table 1 between the pairs of legs 2 and 3 are a pair of brackets 84 supporting a shaft for a reel 85 on which is wound a narrow strip of rubberized fabric 86 in an uncured condition and it is customary to interpose between the windings of the fabric 86 a layer of fabric, generally muslin, to prevent the successive windings from sticking together and the separating layer 87 of cloth is wound onto a

take-up roller 88 supported by pivot arms 89 during the unwinding of the fabric 86. The take up roll is adapted to run on the outer face of the coil of rubberized fabric 86 and receives motion therefrom during the taking-up process. The rubberized fabric 86 is carried upwardly through a suitable opening 90 in the table and over a convex guiding roller 91 and from there is carried forward and applied to the bead core by the following mechanism.

Positioned at the left of the convex roller 91 in Fig. 2 is a pair of housings 93 (see Fig. 7) in which are bearings for the shafts of an upper roller 94 and lower roller 95. The function of the two rollers 94 and 95 is to press the wider and under face of the previously cement coated bead-core against the strip 86 and thereby cause the adhesion of the strip of fabric to this face of the core. The lower roller 95 is provided with lateral flanges 96 for guiding and holding the strip of fabric during its passage between the rolls. These flanges are spaced a sufficient distance apart to easily receive and guide the strip of fabric. The central portion of the roller 95 is provided with shallow circumferential grooves into which the fabric and a portion of the bead are forced by the upper roller 94, the periphery of the latter being fashioned to engage the other two sides of the triangularly-shaped core. As the strip of fabric 86 leaves the rolls 94 and 95 the bead core is adherent to its central upper face and with the unused or unoccupied portions of the strip of fabric projecting laterally from each side of the core. Adjacent to and arranged at the left of the rolls 94 and 95 is an L-shaped member 97 secured to the upper face of the table 1 provided with an upwardly-extending and inclined arm 98 which engages the portion 99 of the fabric on the narrower side of the bead core (see Fig. 13) and its function is to commence the upward folding of the lateral-projecting portion 99. To the left of the member 98 is a folding device denominated generally by the reference numeral 100 (see Fig. 16) and comprising an upright frame 101 on which is a loop-shaped former 102 secured to the frame by bolts having thumb nuts 103 so that the member 102 may be easily removed when desired. Secured to the frame 101 and projecting upwardly in the path of the portion 99 of the strip 86 is a folding member 104 the function of which is to force the portion 99 of the strip 86 inwardly against the sharp or narrower portion of the bead core. The wall of the member 102 which forms the left side of the cavity through which the bead-core passes in Fig. 16 is longitudinally-inclined so as to be engaged by the portion 99 of the strip of fabric and be folded over onto the upper face 105 of the

bead core (see Fig. 14, wherein the application of the portion 99 of the strip is clearly shown).

To the left of the folder 100 and mounted on the table 1 are a pair of rolls 106 and 107 suitably mounted on rotatable axles supported in journal-boxes in housings 108. These rolls 106 and 107 have a portion 109 which engages the remaining smooth portion 110 of the fabric along the side of the bead core and the balance of the peripheries of these two rollers 106 and 107 are so fashioned as to engage the bead core and press the portion 99 of the fabric firmly against the face 105 and cause its adhesion thereto.

Mounted on the table 1 to the left of the housing 108 is a folder denominated generally by the reference numeral 111 and embodying a supporting frame 112 (see Fig. 17) on which is mounted a separable folding device consisting of a lower member 113 provided with shallow conical groove and an upper member 114 removably secured thereto by bolts 115. The upper member 114 is provided with a longitudinal opening registering with the opening in the member 113 and the interior of this common opening in the folder is to mold or press the unused portion 116 of the fabric strip over onto the uncovered portions of the bead core. In order to assist the operation of the folder 111 I provide an upwardly-inclined deflecting member 116 secured to the frame 112 the function of which is to start the folding or bending up of the strip of material, and it is positioned slightly to the right of the folder 111. As already described, the folder 111 will fold the remainder of the unused portion of the strip over the uncovered sides of the bead core and cause the extreme edge thereof to slightly overlap the edge of the already placed portion 99 so that the parts will be arranged substantially as shown in Fig. 15. Immediately to the left of the folder 111 is a pair of housings 117 (see Fig. 9) provided with suitable journal boxes to sustain shafts for a pair of rolls 118 and 119, the peripheral portions of which are fashioned to engage and press the strip of fabric 86 firmly against all faces of the bead core and cause its adhesion thereto.

In order to draw the strip of fabric and the bead core through the mechanism described from the rolls 58 and 59 I provide at the extreme left of the table 1 a pair of housings 118 in which are journaled boxes for a pair of shafts the lower of which bears a sprocket wheel 120 which receives a sprocket chain 122 which runs on a sprocket wheel 123 on the shaft 36 and is thus driven. The shafts in the housings 118 are provided with an upper roller 121 and a lower roller 123 constructed approxi-

mately identically similar to the rolls 58 and 59 which are mounted in the housings 43 and perform the same function. The lower roller 125 being provided with a plurality of teeth for engagement with the bead core and the upper roller provided with a peripherally fashioned face adapted to fit the upper portions of the bead core and force it downwardly against the projections and as the lower roller 25 revolves, it draws the now covered bead core through the mechanism just described.

It is thought that as the functions of the various mechanisms have been given to partly assist in the description thereof, that the entire operation of the machine is clear and a detailed description of the operation is unnecessary.

We claim:

1. In a machine of the class described, the combination with means for progressively moving a bead core, means for trimming the edges thereof, means for coating the core with an adhesive cement, and means for wrapping a strip of fabric about said core during its progressive movement.

2. In a bead-forming machine, the combination of feeding mechanism for progressively moving the bead core, means for trimming the edges thereof, means for coating the exterior of said bead core with an adhesive cement, means for uniting said bead core with a strip of fabric, and means for alternately and successively curling up the edges of said strip and wrapping them on the core.

3. In a device of the class described, the combination of a feeding device for progressively moving a bead core, means for coating the bead core, means for primarily applying a strip of fabric whose edges are adapted to overlap to one face thereof, and mechanism for wrapping the laterally-extending edges of said strip of fabric about said core.

4. In a device of the class described, the combination of a feeding device for progressively moving a bead core, means for coating the bead core with a cement, means for primarily applying a strip of fabric to one face thereof, mechanism for wrapping the laterally-extending edges of said strip of fabric about said core in overlapped relation, and means for pressing the fabric into snug engagement with said core after its placement thereon.

5. In a machine of the class described, the combination of means to move the core progressively forward, means for coating the core with a cement, means for primarily applying a strip of fabric wider than the bead core to one face of the latter, a folding device for folding first one edge and then the other edge of the projecting portions of the strip over said bead core in overlapped relation.

- relation, and means for pressing the strip into snug engagement with the core.
6. A machine of the class described, the combination with means for moving a bead core progressively, mechanism for trimming the edges of the core, means for coating the core with an adhesive cement, means for applying a strip of material to one face thereof, the strip of material being wider than the bead core, a folding device for curling up the projecting edge of the strip on one side, means to press the superposed portion of the strip onto the bead core, means to curl up the opposite side of the strip, and means for pressing said last-mentioned portion of the strip onto said core.
7. A machine of the class specified comprising a feeding mechanism, means for trimming the edges of the core, mechanism for coating the bead core with an adhesive cement, means for partially drying the cement, means for wrapping a strip of material about said bead core, and means for causing its adhesion to said core.
8. A machine of the class described comprising mechanism for moving a bead core progressively, means for trimming the edges thereof, means for coating the bead core with an adhesive cement, means for partially drying the cement, means for wrapping a strip of material about said bead core, and means for causing its adhesion to said core.
9. A machine for covering tire bead cores, comprising the combination with means for unwinding a core from a reel, of means for trimming the core edges, means for coating the trimmed core with an adhesive, and means for wrapping a strip of fabric upon said core during its progressive movement.
10. In a machine for applying a fabric covering to a tire bead core, the combination with means for unwinding a roll of core from a reel, of means for trimming the edges of the core, means for roughening the core surface, means for coating the core with an adhesive liquid, and means for folding the coated fabric upon the moving core.

In testimony whereof we have hereunto set our hands in presence of two subscribing witnesses.
